UNITED STATES PATENT OFFICE.

EMANUEL PAPPERT, OF NEW YORK, N. Y.

DESIGN FOR AN OPTICAL MOUNTING.

Application filed September 6, 1928. Serial No. 28,061. Term of patent 7 years.

To all whom it may concern:

Be it known that I, EMANUEL PAPPERT, a citizen of the United States, residing at the city and State of New York, county of Bronx, have invented a new, original, and ornamental Design for Optical Mounting, of which the following is a specification, reference being had to the accompanying drawing, forming part thereof.

Fig. 1 is a front perspective view of an optical mounting showing my new design.

Fig. 2 is a top plan view of the same.

I claim:

The ornamental design for an optical mounting, as shown.

EMANUEL PAPPERT.
